DESIGN FOR A HAT

Lilly Daché, New York, N. Y.

Application June 13, 1939, Serial No. 85,472

Term of patent 14 years

To all whom it may concern:

Be it known that I, Lilly Daché, a citizen of the United States, residing at No. 78 East 56th Street, in the city, county, and State of New York, have invented a new, original, and ornamental Design for a Hat, of which the following is a specification, reference being had to the accompanying drawing forming a part thereof.

Fig. 1 is a side view in perspective of a hat showing my design;

Fig. 2 is a front perspective view of the hat shown in Fig. 1.

The dominant features of my design are shown in solid black lines in the drawing.

I claim:

The ornamental design for a hat, substantially as shown and described.

LILLY DACHÉ.
